UNITED STATES PATENT OFFICE

JOHN S. O'HARE, OF BETHUNE, COLORADO

SCREED SUPPORT

Application filed November 1, 1929. Serial No. 404,071.

This invention relates to improvements in screed supports of the type employed in connection with the construction of concrete floors and sidewalks and has reference more particularly to an improved form of screed supports of the type shown and described in my copending application Serial No. 259,408, filed March 6, 1928.

The use of concrete as the building material for buildings of all kinds is rapidly increasing, and it is therefore necessary to provide special tools so as to facilitate the construction of different parts thereof.

In the floor constructions of buildings of this type, it is necessary to employ screeds which must be carefully levelled and put in place before the concrete is poured, as by this means only can the surface of the floors be made smooth and level.

In the application above referred to, I have shown and described the screed support comprising U-shaped members having pointed ends and which are secured to an angle iron or a wooden screed. I have found that it is very desirable to be able to adjust the height of the screed supports so that floor constructions of different thickness can be provided for and so that the screeds can be very easily levelled, regardless of whether the false work on which the floor is moulded is level or not.

It is the object of this invention to produce screed supports that shall be adjustable and which shall be so constructed that when put in place they will hold the screed very rigidly in adjusted position, and which can be readily removed after the floor has been laid.

The above and other objects which may become apparent as the description proceeds are attained by means of a construction and an arrangement of parts that will now be described in detail, reference for this purpose being had to the accompanying drawing in which the preferred embodiment of the invention has been illustrated, and in which:

Fig. 1 is a section through the false work on which a floor is laid and shows one of my improved screeds in place thereon;

Fig. 2 is a section taken on line 2—2, Fig. 1;

Fig. 3 is a section taken on line 3—3, Fig. 2;

Fig. 4 is a section similar to that shown in Fig. 2, but shows a slightly modified form of construction;

Fig. 5 is a section taken on line 5—5, Fig. 4; and

Fig. 6 is a transverse section showing a straight edge applied to the upper surface of two screeds.

In the drawing numeral 1 represents the surface on which the concrete slab forming the floor is supported during construction. In the construction of concrete building a false work is usually erected and a support formed by planks 2 is provided for supporting the concrete during construction and while it is setting. The supporting surface is very difficult to construct so that it will be perfectly level and at such height that all of the floors will be the same thickness. The upper surface of the finished floor must be perfectly level and must be at a certain height so as to correspond with the other floors of the building.

For the purpose of enabling the concrete worker to lay the concrete floor slab in such a way that its upper finished surface will be perfectly level and at the right height, either wooden or metal screeds, such as those indicated by reference numeral 3 are provided. These screeds are spaced suitable distances apart and are carefully levelled and adjusted as to height. It is, of course, evident that some means must be provided for supporting these screeds in such a manner that they will remain in adjusted position during the construction of the floor.

This invention relates to the construction of the screed supports which, in the embodiment shown are formed from channel iron having two parallel side members 4 and 5 which are connected at one end by a base 6 so as to form a substantially U-shaped structure. In the preferred embodiment, the channel is on the inside of the side members, but the supports would operate even if they were bent in such a manner that the channels were to the outside. A number of these U-shaped supporting members are secured to the inside of an angular screed 3 by means of rivets or bolts 7. The number of supports

varies with the length of the screed but with an ordinary length, as, for example, twelve or fourteen feet, four of these members are usually employed and are spaced equidistantly along the screed. Each of the side members 4 and 5 is provided with slots 8 that extend substantially the entire length thereof. Since the flange of the angle iron screed extends downwardly along the side member 5, the slot 10 in this member usually terminates at the lower edge of the flange. Located in the channel of each of the side members 4 and 5 are bars 9 and 10. These bars are of such size that they will fit the channel in the side 15 members and the flanges of the channel iron will therefore serve as guides to hold the arms 9 and 10 steady. Bar 9 is preferably provided with three holes 11 which are spaced equidistantly apart and which are adapted to 20 receive clamping bolts 12 that extend through the slot 8 and which are provided with nuts 13 that serve to clamp the arm to the side member. It is evident that by loosening the bolts 12 the bar can be moved longitudinally 25 with respect to the side member 5 and that it can be clamped in any desired position. When the support is to be extended to its utmost capacity the lower bolt is moved to the upper hole but for ordinary uses the two 30 bolts are located as shown. The lower ends of bars 9 and 10 are pointed as indicated by reference numeral 14 in Fig. 1. These pointed portions terminate in shoulders 15 that form stops which limit the penetration of 35 these bars into the false work 2. Bar 10 is constructed exactly like bar 9 with the exception that the lower hole 11 is omitted as it is not necessary on this side of the support for the reason that the slot 8 extends practically 40 the entire length of side member 4.

In Fig. 2 I have shown bars 9 and 10 secured to the sides of the support by means of bolts having nuts 13. These nuts naturally become imbedded in the concrete and therefore serve to anchor the supports and when 45 nuts are employed in the manner shown, the supports must be removed before the concrete becomes too hard as otherwise it is necessary to chisel part of the concrete away before the supports can be removed.

In Fig. 4 I have shown bolts 12 replaced by screws 16 which have countersunk heads and I have also shown how the slots can be provided with bevel sides 17 that accommodate the inside sides of the heads 16. The bars 9 and 10 have threaded openings with which these screws engage and when screws of this type are employed instead of bolts, there are no projections that anchor the supports to the concrete and therefore it is possible to remove them even after the concrete has hardened. For the purpose of preventing the concrete from adhering too strongly to the surfaces of the support the latter may be covered with a thin film of oil that will

prevent adhesion between the concrete and the metal surfaces of the support.

It is only necessary to provide the end supports with points 14 and therefore the intermediate supports have been shown as lacking 70 this element.

When the screeds are put in place, the height is accurately determined and the support at one end is adjusted to bring the upper surface of the screen at the exact level desired for the finished floor. After one end support has been adjusted and put in place, the workmen then adjust the other support, after which the intermediate supports are adjusted. The construction shown holds the 80 screeds in adjusted position and therefore greatly facilitates the use of these screeds. After the concrete has been filled in to the desired thickness, a straight edge like that indicated by reference numeral 18 is run back 85 and forth along the upper surfaces of the screeds and this brings the surface of the concrete into a plane that coincides with the upper surfaces of the screed. In the drawing the two sides of the U-shaped supports have 90 been shown parallel and this is the preferred construction as it permits the supports to be readily withdrawn from the concrete. It is possible, however, to spread the sides apart slightly and I therefore do not want to be 95 limited strictly to having the two sides in parallel relation.

Although these supports are intended primarily for use in laying floors in buildings they can, however, be employed in connection with the laying of sidewalks and other outside pavements in which case the bars 9 and 10 are driven into the ground so as to hold the screeds at the proper level.

In the drawing the U-shaped support has 105 been shown as formed from channel iron, as this is believed to be the most suitable for this purpose. It is apparent, however, that ordinary strap iron can be used, as by employing two bolts that extend through the 110 slot of each side member, the bars 9 and 10 will be guided quite effectively even if no flanges are present for this purpose.

From the above description it will be apparent that I have produced a simple and 115 substantial screed support than can be readily adjusted so as to accommodate the screed to floors of different thicknesses, and by means of which the screeds can readily be 120 adjusted so as to lie in a perfectly level plane even when the supporting surface of the false work is not level.

Having described the invention what is claimed as new is:

1. A screed support, comprising an inverted U-shaped member having two spaced substantially parallel sides, a separate bar slidably connected with each side and means for clamping the bars to the sides. 120

2. A screed support, comprising an inverted **U**-shaped member having two spaced substantially parallel sides, a separate bar slidably connected with each side and means for clamping the bars to the sides, said bars having pointed ends adapted to be driven into a support.
3. A screed support comprising, an inverted **U**-shaped member having two spaced substantially parallel sides, each having a slot extending in the direction of its length, a separate bar adjustably connected with each side and clamping means extending through the slot for securing the bar in adjusted position.
- 10 4. A screed support comprising, an inverted **U**-shaped member having two spaced substantially parallel sides, each having a slot extending in the direction of its length,
- 20 5. A screed support comprising, an inverted **U**-shaped member of channel cross section having two spaced, substantially parallel sides, a separate bar located in the channel of each side, said bars being longitudinally adjustable, and means for holding
- 30 6. A screed support comprising, an inverted **U**-shaped member of channel cross section having two spaced, substantially parallel sides, a separate bar located in the channel of each side, said sides and bars having connecting means comprising a slot in one of said members and two bolts connected with the other member, said bolts passing through the slots and, when tightened, holding the bars in adjusted position with respect to the sides.
- 35 7. A screed support comprising, an inverted **U**-shaped member adapted to be secured to one side of the screed, said member having a channel extending longitudinally thereof, each of the sides of said member having longitudinally extending slots, a separate bar associated with each slot, said bars lying in the channels and clamping bolts
- 40 50 passing through the slots for holding the bars in adjusted position.

In testimony whereof I affix my signature.
JOHN S. O'HARE.
